METHOD OF FORMING HEAT TRANSFER UNITS

Richard W. Kritzer, % Peerless of America,
5830 N. Pulaski Road, Chicago, Ill.
Filed June 14, 1956, Ser. No. 591,488
1 Claim. (Cl. 29—157.3)

The invention relates to heat transfer units which include tubing and fins and to the fabrication thereof.

One object of the invention is to provide a fin-structure which is adapted for use with a variable number of tubing sections, fins of varying length to extend over areas of variable dimensions, for heat-transfer units of different capacities.

Another object of the invention is to provide an improved method of fabricating a fin-structure which is adapted for uses with different numbers of tubing sections and to provide finned areas on the tubing of varying dimensions.

Other objects will appear from the detailed description.

The invention consists in the several novel features which are hereinafter set forth and more particularly defined by the claim at the conclusion hereof.

In the drawings:

FIG. 1 is a plan view of a continuous web of fin-stock which has been fabricated with openings for the tubing sections surrounded by annular flanges, ribs producing turbulence and perforations, through which air can pass, preparatory to severing the web longitudinally into fin-strips for assembly with tubing;

FIG. 2 is a section taken on line 2—2 of FIG. 1 on a larger scale;

FIG. 3 is a section taken on line 3—3 of FIG. 1 also on a larger scale;

FIG. 4 is a section taken on line 4—4 of FIG. 1 also on a larger scale;

FIG. 5 is a longitudinal section of one of the fin-strips bent into serially connected sections preparatory to its assembly with tubing;

FIG. 6 is a plan view of an assembled heat transfer unit;

FIG. 7 is a partial side elevation of the assembled unit, the tubing being shown in section;

FIG. 8 is a partial section taken on line 8—8 of FIG. 7;

FIG. 8a is a section taken on line 8a—8a of FIG. 8;

FIG. 9 is a plan view of the stationary bed of a press and tools mounted thereon used for forming the openings for the tubing, annular flanges around said openings and the ribs on the web, the guides for the reciprocable head being shown in section;

FIG. 9a is a section taken on line 9a—9a of FIG. 9;

FIG. 10 is a vertical longitudinal section of the coacting tools on the stationary bed and the reciprocable head of the press, taken on line 10—10 of FIG. 9;

FIG. 11 is a section illustrating the tools for forming bulges on the web of fin-stock;

FIG. 12 is a section illustrating the tools for piercing or rupturing the bulges formed on the web preparatory to shaping them into annular flanges;

FIG. 13 is a section illustrating the dies for accurately shaping the annular flanges around the openings for the tubing; and

FIG. 14 is a section illustrating one of the stripper-plungers.

The invention utilizes an elongated or continuous web of fin-stock which is supplied from a coil of great length on a reel, and which is severable into elongated strips which are bendable transversely to form serially connected fin-sections. Series of longitudinally spaced openings, each surrounded by an annular flange, are formed

2

in longitudinal zones of the web of fin-stock and the longitudinal zones are severed from one another by longitudinal cuts to provide elongated strips. The fin-stock is transversely bendable to form series of fin-sections of varying lengths according to the desired number of tubing-sections and the desired area thereof to be provided with fins. This adapts like strips of fin-stock to be utilized in the fabrication of heat transfer units which include tubing-coil sections of varying numbers and finned areas of varying dimensions. Like fabricated stock is available for the expeditious fabrication of units with different numbers and dimensions of coil-sections and variable finned areas. This results in economy in the cost and expedites the production of assembled units of different commercial specifications.

In the fabrication of the units, a web of suitable fin-stock 20 is usually fed from a supply reel. The web may be of any suitable width and may be of sheet aluminum of .006" in thickness which is flexible and highly efficient in heat conduction. Symmetrical longitudinally spaced series of openings 21 for receiving tubing-sections 22 are formed in symmetrically and transversely spaced series across the web. Each opening 21 is surrounded by an annular flange 23 projecting from one face of the web. The alternate flanges in each longitudinal series extend from opposite faces of the web, as shown in FIG. 2. At each side of each opening 21 and flange 23 the web 20 has embossed ribs 24 for producing turbulence in the air flow between fin-sections in the assembled units. The ribs 24 at the sides of alternate openings 21 in each longitudinal series, project from the opposite faces of the web. Perforations 25 are formed in the web 20 between the longitudinally adjacent openings 21 to permit some air to flow through fin-sections. The annular flanges 23 provide increased contact area between the tubing and the fin-sections and also function to space the sections apart in the assembled units. After the web has been provided with the longitudinal series of openings 21, flanges 23, ribs 24 and perforations 25, it is severed longitudinally along dotted lines 26 to form elongated fin-strips 27 of great length, each strip having a longitudinally and symmetrically spaced series of openings 21 adapted to receive a section of tubing of a predetermined diameter, flanges 23 surrounding the openings 21 and alternately projecting from opposite faces of the web, ribs 24 projecting from the opposite faces of the web at the sides of alternate openings 21 and perforations 25 in the web between said openings. In this manner there is produced from the web, a multiple or series of strips 27 of the desired width, in any desired length, and bendable as at 29, into a fin-structure. These strips are bendable transversely at different points, preferably across perforations 25 to provide fin-sections of varying length, or for units of different dimensions or varying numbers of tubing-sections. In this manner, a stock can be maintained of strips for the fabrication and assembly of units of different dimensions or capacity and different numbers of tubing sections.

In assembling the heat transfer units, a strip 27 with the openings 21, flanges 23 and ribs 24, is bent as at 29 transversely and severed from the web approximately into the contour shown in FIG. 5 to form fin-sections 27a each with the number of openings 21 and flanges 23 corresponding to the number of tubing-sections to be included in the unit and in length corresponding to the number of sections desired in the finned area of the unit. A sufficient number of these sections are bent to provide a number of fins for the desired width of the finned area of the unit, and for continuity are serially connected by bends alternately between opposite ends of contiguous sections. Tubing sections 30 slightly less in diameter than the openings 21 are then inserted se-

rially through said openings and the sections 27a are forced together until they are substantially parallel between the bends 29, and the openings 23 in the sections will be aligned so that tubing-sections 30 for the entire unit can be inserted through fin-sections as shown in FIG. 6, with the flanges 23 spacing said sections apart for the flow of air. Next, the tubing-sections are expanded by forcing a suitable mandrel through the tubing-sections or by internal fluid pressure, for forcing the outer periphery of the tubing into pressure-contact with the inner peripheries of said flanges and for efficient heat conduction. Connecting bends 31 are then serially connected to the ends of the tubing sections to form a coil for the flow of refrigerant therethrough while the fin-structure conducts heat to the ambient atmosphere. The unit will then be completely assembled for use.

The openings 21, flanges 23 and ribs 24, in multiple, are formed in the web 20 for their simultaneous formation in transverse zones of a set of said openings, flanges and ribs, and consecutively in the longitudinal zones which are severed into strips 27 by suitable tools in a power press which includes a stationary bed *a* and reciprocable head *b* which is operable by any suitable power driven mechanism. Multiple sets of tools are provided, one for each longitudinal zone of the web which is subsequently severed into strips 27 and are disposed in side-by-side relation in the press. Each set of tools is adapted to form consecutively along one of said zones, a pair of openings 21 with surrounding flanges 23, associated ribs 24, and perforations 25, during successive operations of the press and step-by-step advances of the web. Each of said sets of tools includes tools mounted on the bed *a* and mating or coacting tools mounted on the head *b*. Collectively, the multiple sets of tools form the openings 21, flanges 23 and ribs 24 in the entire series of longitudinal strip-forming zones of the web. The tools of each set are of like construction, respectively. The tools on the bed *a* are mounted on a pair of plates *a*¹ and *a*² which are demountably secured on said bed and the coacting tools on head *b* are demountably secured on plates *b*¹ and *b*² which are movable with said head, for convenience in assembly and replacement of said tools. The plates *a*¹ and *a*² function as a part of the bed or stationary member of the press and the plates *b*¹ and *b*² function as a part of the head or movable member of the press.

Each set of tools for forming the annular flanges 23, includes a deforming tool 35 which is secured in plates *a*¹ and *a*² on bed *a* and a coacting socket 36 in plate *b*¹ which are adapted to form an upward bulge 37 on the web 20 and a tool 38 which is secured in plates *b*¹ and *b*² on head *b* and coacts with a socket 39 in plate *a*¹ for forming a downward bulge or deformation 40 on the web 20 in longitudinal alignment with bulge 37, during each operation of the press, as shown in FIG. 11. The entire web will next be advanced one step to position the bulges 37 between a deforming tool 42 on head *b* and a socket 43 on plate *a*¹ on bed *a* and to position bulge 40 between a tool 44 in plates *a*¹ and *a*² and a spring-pressed slidible plunger 45 in plate *b*¹ and *b*². When the web is thus advanced and head *b* is again operated, the bulge 37 will be deformed or stretched into a pierced bulge 47 and bulge 40 will be simultaneously re-shaped as shown at 48 in FIG. 12. The web 20 is next advanced longitudinally to vertically align bulge 47 with a punch 49 in plate *b*¹ and a socket 50 in plates *a*¹ and *a*² and to simultaneously align bulge 48 with a punch 51 in plates *b*¹ and *b*² of head *b* and a socket 52 in plates *a*¹ and *a*² as shown in FIG. 10. When the press is again operated the punches 49 and 51 will cut disks from the previously deformed portions 47 and 48 and discharge them through the downwardly flared openings in sockets 50 and 52 in plates *a*¹ and *a*² and bed *a*, flanges will be formed to surround the openings 21 and project from opposite faces of the web. The

web is next advanced to axially align one flange 23 with a female die 55 in plates *a*¹ and *a*² and a male die 56 in plates *b*¹ and *b*² and to axially align the other flange with a male die 57 in plates *a*¹ and *a*² and a female die 58 in plates *b*¹ and *b*². During the next stroke of the head *b* of the press, these dies will produce uniform annular flanges 23 projecting from opposite faces of the web between the dies 59 and 56 and dies 57 and 58, respectively, as shown in FIG. 13 for accurate surrounding correlation with tubing extending through the openings 21. Perforations 25 are punched in the web by a pair of punches 62 which are mounted in plates *b*¹ and *b*² and a mating pair of female dies 63 which are mounted in plates *a*¹ and *a*².

15 Each set of tools on the press includes a pair of dies 70 (FIGS. 9 and 9a) confined in plate *a*¹, each of which has a rib 71 and a longitudinally aligned recess 72 which coacts with a pair of dies 74 in plate *b*¹, each of which has a recess 76 coacting with rib 71 and a rib 20 75 coacting with recess 72 to bend pairs of ribs 24 in the sheet 20 at the sides of each flange 23 when said flanges are being shaped between dies 55 and 56, and 57 and 58, the ribs projecting alternately from opposite faces of the sheet 20.

25 Successive strokes of the press operate these tools to produce a web with longitudinal series of longitudinally spaced openings 23 surrounded by annular flanges 23 projecting alternately from opposite faces of the web, ribs 24 projecting alternately from opposite faces of the web, and perforations 25 between openings 21. The web is produced with multiple transverse series of these formations so that the web when severed along the lines 26 will provide strips of fin-stock which is bendable transversely into strips 27 for use in assembling a continuous strip of fin-structure with the tubing to complete the units.

30 Series of plungers 68 are vertically slidable in plates *a*¹ and *a*² and their upper ends are adapted to support the web 20 of fin-stock between the tools in position to be operated upon by the press. Each plunger is slidably mounted in plates *a*¹ and *a*² and has a shoulder 61 for limiting its upward movement by a spring 69 which is confined in plates *a*¹ and *a*² of the bed. The plungers 45 68 are provided at the points necessary for initially supporting the web 20 above the tools on bed *a*. Springs 69 permit the web to be forced down to plate *a*¹ during each down stroke of head *b* and force said web after each operation to release or strip the web from the tools for successive steps of advance and successive operations 50 of the tools on consecutive portions of the web.

55 When the web has been severed on lines 26 to form strips 27, the latter may be bent on transverse lines to produce strip-sections of different lengths and for different numbers of tubing-sections, and with finned areas of any desired widths so that fabricated strips will be available for expeditiously and economically assembling fabricated strips 27 and tubing-sections for heat transfer units of different dimensions. For example, the strips may be bent to provide serially connected sections 27a with openings 21 and flanges 23 for a unit with six or any other desired number of tubing sections or sections for finned areas of different widths or lengths of the tubing sections. The fabricated strips are also usable on tubing which is circular or spiral in contour because of the flexibility of the strip.

60 The invention is not to be understood as restricted to the details set forth since these may be modified within the scope of the appended claim without departing from the spirit and scope of the invention.

65 70 Having thus described the invention what I claim as new and desire to secure by Letters Patent is:

75 The method of fabricating finned heat transfer tubing from a flat strip of sheet metal stock and cylindrical tube stock which comprises: establishing a series of equally spaced parallel fold lines transversely of the strip and

medially of the ends thereof, forming in said strip a small perforation at each established fold line, forming in said strip between each adjacent pair of fold lines a row of spaced circular tube openings surrounded by annular flanges which project out of the plane of the stock with said rows extending in alignment, the spacing of the openings on opposite sides of each fold line being identical so that when the strip is folded on said fold line the openings will be brought into approximate axial alignment in pairs, the annular flanges which are equally spaced from each fold line extending in opposite directions, folding said strip on said fold lines alternately in opposite directions to thus bring said openings into such approximate alignment with the flanges of the approximately aligned openings extending in the same general direction and to thus create oppositely facing notches at alternate fold lines respectively, inserting a length of cylindrical tube stock through each series of approximately aligned openings and, finally, expanding the tube stock lengths into intimate face-to-face frictional contact with the inside 20 surfaces of the flanges through which they project.
